CLAIM

The ornamental design for a shaped charge frame, as shown and described.

DESCRIPTION

FIG. 1 is an isometric view of the first embodiment of a shaped charge frame at a first top angle; FIG. 2 is an isometric view of the shaped charge frame of FIG. 1 at a second top angle;

FIG. 3 is an isometric view of the shaped charge frame of FIG. 1 at a third top angle;

FIG. 4 is an isometric view of the shaped charge frame of FIG. 1 at a first bottom angle;

FIG. 5 is an isometric view of the shaped charge frame of FIG. 1 at a second bottom angle;

FIG. 6 is an isometric view of the shaped charge frame of FIG. 1 at a third bottom angle;

FIG. 7 is a side view of the shaped charge frame of FIG. 1 at a first angle;

FIG. 8 is a side view of the shaped charge frame of FIG. 1 at a second angle;

FIG. 9 a side view of the shaped charge frame of FIG. 1 at a third angle;

FIG. 10 is a side view of the shaped charge frame of FIG. 1 at a fourth angle;

FIG. 11 is a top view of the shaped charge frame of FIG. 1; FIG. 12 is a bottom view of the shaped charge frame of FIG. 1;

FIG. 13 is a cross-sectional view of the shaped charge frame of FIG. 7 taken along section line 13; and

FIG. 14 is a cross-sectional view of the shaped charge frame of FIG. 7 taken along section line 14.

FIG. 15 is a cross-sectional view of the second embodiment of a shaped charge frame along the first longitudinal section; FIG. 16 is an isometric view of the shaped charge frame of FIG. 15 at a first top angle;

FIG. 17 is an isometric view of the shaped charge frame of FIG. 15 at a second top angle;

FIG. 18 is an isometric view of the shaped charge frame of FIG. 15 at a first bottom angle;

FIG. 19 is an isometric view of the shaped charge frame of FIG. 15 at a second bottom angle;

FIG. 20 is a side view of the shaped charge frame of FIG. 15 at a first angle;

FIG. 21 is a side view of the shaped charge frame of FIG. 15 at a second angle;

FIG. 22 is a side view of the shaped charge frame of FIG. 15 at a third angle;

FIG. 23 is a side view of the shaped charge frame of FIG. 15 at a fourth angle;

FIG. 24 is a top view of the shaped charge frame of FIG. 15; FIG. 25 is a bottom view of the shaped charge frame of FIG. 15;

FIG. 26 is a cross-sectional view of the shaped charge frame of FIG. 15 along a lateral section; and,

FIG. 27 is a cross-sectional view of the shaped charge frame of FIG. 15 along a second longitudinal section.

The broken lines in the drawings show environmental structure and form no part of the claimed design.
